UNITED STATES PATENT OFFICE.

JAMES W. WHITE, OF BAINBRIDGE, GEORGIA.

WINDOW.

1,844,529.

Specification of Letters Patent. Patented June 22, 1920.

Application filed October 10, 1916. Serial No. 124,905.

To all whom it may concern:

Be it known that I, JAMES W. WHITE, a citizen of the United States, residing at Bainbridge, in the county of Decatur and State of Georgia, have invented new and useful Improvements in Windows, of which the following is a specification.

This invention relates to a window construction and more particularly to a construction which will provide a combined window and blind.

The primary object of the invention is to provide a device of this character in which a frame has mounted for independent sliding movement therein a blind and three sashes, with one of the sashes having adjustably mounted thereon a pair of blinds and so arranged with relation to the other sashes that by adjusting the sashes with relation to each other and the blinds, the proper lighting and ventilation of the chamber in which the window is located will be assured.

Another object of the invention is to provide one of the sashes with both transparent and translucent panels over which the pair of blinds adjustably mounted upon the sash may be arranged as found desirable when the sash is adjusted within the frame with relation to the other sashes and the sliding blind within the window frame.

With these and other objects in view, the invention resides in the novel combination and arrangement of parts, which will be hereinafter described and particularly pointed out in the claim.

The preferred embodiment of the invention has been illustrated in the accompanying drawings, although no restriction is necessarily made to the precise details of construction therein shown, as changes, alterations, and modifications, within the scope of the claim may be resorted to when desired.

Like characters of reference denote corresponding parts throughout the several views in the drawings, in which:

Figure 1 is a view in elevation of a window constructed in accordance with the invention, the sliding sashes and blind being shown in position to close the opening in the window frame.

Fig. 2 is a vertical transverse section on the line 2-2 of Fig. 1.

Fig. 3 is a transverse section on the line 3-3 of Fig. 1.

Fig. 4 is a view in elevation of one of the sashes, and showing the blind thereon adjusted to cover one of the transparent panels in the sash.

Fig. 5 is a horizontal transverse sectional view on the line 5-5 of Fig. 4.

Referring now to the drawings in detail, the letter A designates a window frame in which is arranged a top sash B, a middle sash C, a lower sash D, and a blind E of equal heights, said sashes and blind being spaced apart by parting strips 6 on the side stiles of the window frame A and forming channels in which said sashes and blind may have independent sliding movement, the blind E being held in adjusted position within the frame by suitable latch members 7 engageable with the frame for this purpose while the sashes may be supported in adjusted position within the frame A by the usual counter-weights and cords 8.

The upper sash B and the lower sash D are each provided with a single transparent panel 9 while the middle sash C is provided with sash bars 10 coacting with the stiles and rails of the middle sash in supporting panes 11 and 12 arranged in pairs. The pair of panes 11 which are arranged above the pair of panes 12 are formed from transparent material while the panes 12 are of translucent material, such as stained glass, or the like.

Each side stile and one sash bar of the middle sash C have secured thereto retaining strips 13 coacting with the side stiles and cross bar in forming within the sash C longitudinally extending channels 14 in which are mounted to slide a pair of auxiliary blinds 15 arranged upon opposite sides of the sash bar 10 with which one of the retaining strips 13 is connected, said blinds 15 being adapted to be held in adjusted position within the channels 14 to cover either the panes 11 or 12 as the occasion requires by means of suitable latch members 16 connected with the blind frames and adapted for contact with the retaining strips 13.

Each of the auxiliary blinds 15 comprises a frame 17 having extending transversely thereof spaced and overlapping slats 18 so that when the blinds are arranged within the channels 14 in the sash C to cover the panes 11, the auxiliary blinds will coat with the panes 12 in preventing a person 116 from looking through the sash C.

Through the above described arrange-

ment of the sashes B, C, and D within the frame A, it will be seen that the sashes may be slid to a position within the frame A to expose practically two-thirds of the opening within the frame A so that a greater quantity of air may enter the chamber in which the combined window and blind is located than is possible with the window now in common use or the sashes may be 5 adjusted within the frame to obstruct the passage of air through the opening therein at any point found desirable while the light passing through the middle sash C may be regulated through the adjustment of the 10 auxiliary blinds 15.

The blind E is slidably mounted in the frame A and consists of a frame 19 extending transversely of which are overlapping slats 20 which permit the passage of air 20 through the blind E. When desired the blind E may be adjusted within the frame A to control the passage of light through the sashes B and D. When the blinds 15 are adjusted upon the sash C to overlie the

transparent panes therein and the blind E 25 and sashes B, C and D are in the position shown in Fig. 2 in the drawing it will be apparent that an occupant of a room in which the window is located will be protected from the gaze of a person passing the 30 window.

From the foregoing description, taken in connection with the accompanying drawings, it is at once apparent that a window has been provided which though inexpensive of manufacture is highly efficient for the purposes stated.

Having thus described the invention, what is claimed as new, is:

The combination with a window sash, of 40 shoulders formed longitudinally of the sash stiles and spaced from the window pane, retaining strips secured to the face of the sash and spaced from the shoulders to define grooves and a member mounted for sliding 45 movement in the grooves.

In testimony whereof I affix my signature.
JAMES W. WHITE.
